METHOD OF STORING AND USING HEAT
AND MEANS THEREFORJohn J. Grebe, Midland, Mich., assignor to The
Dow Chemical Company, Midland, Mich., a cor-
poration of Michigan.

Application July 7, 1930, Serial No. 465,826

6 Claims. (Cl. 122—35)

My invention relates more particularly to storing up heat liberated by fuel employed for generating steam in a boiler, chiefly during periods of low or moderate demand therefor, and the reuse 5 of the so stored heat to generate steam in addition to that generated directly from the fuel in the steam boiler, in response to demands for steam during peak loads on the boiler. The invention relates still more specifically to the employment of diphenyl oxide or other high boiling fluid stable at high temperatures as the fluid medium for storing and/or transferring heat to storage preferably in a suitable solid material such as cast iron.

15 The use of steam accumulators in which the heat of steam is stored as sensible heat of water under pressure is old, as is the reuse of the so stored heat in the form of steam. In order to generate steam from the heat so stored in water, 20 the pressure thereon must be reduced materially and the steam so generated will have a lower pressure and the heat content thereof will have a lower availability than the same heat in the higher pressure boiler steam.

25 The use of accumulators employing a high boiling fluid such as phenanthrene is not new per se, it having been proposed to boil phenanthrene in a boiler employing fuel and to vaporize water in a steam generating element exposed to the phenanthrene vapor over a body of hot phenanthrene. In this proposal the steam produced during excess demands will have a lower temperature than the steam normally produced, and, as in the previous instance employing a steam accumulator, 30 the availability of the stored heat will be progressively lowered as used.

It has been further proposed to store heat in a large body of boiler feed water outside of the boiler proper and upon the occasion of excess 40 demands for steam to use such stored high temperature-high pressure water as boiler feed. This proposal has advantage over the previously mentioned steam accumulator method, but requires that there shall be sufficient steam liberating and separating capacity in the boiler to care for the extra steam produced, sufficient excess superheater capacity to superheat the extra steam, the inclusion of which in the boiler adds to the investment and reduces the economy otherwise obtainable from the use of an accumulator in ironing out peak loads.

It is accordingly highly desirable to provide a method and means, costing less than the equivalent additional capacity in boilers, etc., to absorb 55 heat in an accumulator system during off-peak

steam loads and to deliver to the power mover therefrom steam at substantially full boiler pressure and temperature at the time of demand for excess steam. If in doing this the investment in, 60 and operating charges for, the accumulator system are less than for the excess boiler capacity, economic limitations will have been met, and it is the object of this invention to afford such a method and means whereby the heat of fuel, preferably waste heat, going to the stack shall be stored in a 65 high boiling fluid and shall be reusable to produce steam therefrom at full boiler pressure and temperature, insuring a constant pressure heat storage system which will produce high pressure 70 superheated steam and preheated boiler feed water during peak loads.

To the accomplishment of the foregoing and related ends, the invention, then, consists of the steps and means hereinafter fully described and particularly pointed out in the claims, the annexed drawing and the following description setting forth in detail certain means and modes of carrying out the invention, such disclosed means and modes illustrating, however, but 75 several of the various ways in which the principle 80 of the invention may be used.

In said annexed drawing:—

Fig. 1 represents in partly diagrammatic fashion a storage system and Fig. 2 represents one type of tubular heating unit employed therein.

I have found that diphenyl oxide, which has become recently available in quantity at a reasonable price, has peculiarly advantageous properties for use in a heat storage system. Its melting point is low, approximately 80.6° F., which insures practical immunity from freezing in pipes, valves, etc., under conditions obtaining in operation of heat storage systems. It is stable under prolonged heating at 700° F., and subject to only slight decomposition above 725° F. Its specific heat, liquid, is in the neighborhood of .45. At 700° F. the vapor pressure is approximately 100 pounds absolute or 85 pounds gauge which low pressure at high temperature permits the storage under pressure of a large volume of diphenyl oxide in containers of moderate thickness, whereas when heat is stored in water at high temperature the pressure rises to boiler pressure and even limited volumes require heavy expensive storage vessels. Diphenyl oxide further possesses the 95 property of high fluidity. It does not act upon iron at the temperatures involved and has a high rate of heat transfer to and from an iron surface. Although I prefer to employ diphenyl oxide because of its unique properties, making it admi- 100 105 110

rably suited for the purpose in hand, my invention is not restricted to the use of diphenyl oxide, but there may be substituted and employed therefor other high boiling point substances or admixtures of other ingredients with the same or with diphenyl oxide without departing from the spirit of my invention.

In order to increase the heat storage capacity of a given body of diphenyl oxide, I employ a solid material of relatively high specific heat, such as cast iron, which may be in the form of pigs or other convenient economic shape which I submerge in the diphenyl oxide in the storage tank therefor. Such iron or equivalent takes on the same temperature as the diphenyl oxide which is in contact with it, the heat coming into the storage tank with the diphenyl oxide being shared with the iron automatically upon contact therewith. In order to store the heat in the diphenyl oxide, I prefer to install in the path of the stack gases, after the boiler proper, either before or after an economizer, or before an air preheater, or in a by-pass around an air preheater, a suitable amount of heating surface which may be of iron tubes and to circulate continuously a current of the diphenyl oxide through such a heater in countercurrent relation to the stack gases. I prefer to draw the diphenyl oxide from the bottom or cold portion of the storage tank and to discharge the heated diphenyl oxide from the heater into the upper or hot portion of the storage tank. In this way the contents of the storage tank, including the iron therein, may be eventually brought up to a uniform high temperature accomplishing the storage therein of a large amount of heat at a high temperature level. Since the hot diphenyl oxide entering the storage tank will divide its sensible heat with the iron, it is preferable to gauge the rate of circulation so that during periods in which reuse of the stored heat it not required the entire body of diphenyl oxide shall have passed through the heating zone more than once so as to finally bring up the temperature of both iron and diphenyl oxide in the storage tank to a temperature above boiler temperature. In order now to return the so stored heat to the power system, I pass a current of water through a water heating and steam generating element in heat transfer relation with the diphenyl oxide whereby such water is heated and vaporized. In order that steam shall be made in that way, having a pressure and temperature substantially that of the boiler steam, I prefer to circulate the stored heated diphenyl oxide in countercurrent heat exchange relation with the current of water from which the steam is to be produced. In this way the last pass of the water through the steam generating element will be exposed to the hottest diphenyl oxide whereby superheated steam of full boiler pressure may be obtained, and by providing a proper circulatory heat exchange system between the so cooled diphenyl oxide and the hot iron in the storage tank substantially all of the heat stored in the iron as well as that in the diphenyl oxide may be transferred to the water for the production of such superheated high pressure steam, until finally the temperature of the diphenyl oxide and the iron has been reduced to a temperature approximating that of the water entering the steam generating element. A preferred arrangement of the circulatory system will be hereinafter described.

I find that my invention may be economically introduced into existing or contemplated steam

power plants or central heating systems and the like at a total investment charge less than required if the initial capacity of the boiler plant be figured for the peak load and that my improved system may be operated at a lower cost.

Referring to the drawing, 1 is a closed storage tank charged with diphenyl oxide to the level 2-2' leaving a vapor space 3 to allow for expansion. A vapor space outlet 4 leads to a purging condenser 5 provided with a valve vent 6. The condenser is here shown as an air cooled chamber in which diphenyl oxide vapor will condense and run back into tank 1 permitting the venting of non-condensable gases, such as air, when desirable, without venting a material amount of diphenyl oxide vapor.

Within the tank 1 is an inner tank or shell 7, forming with tank 1 an annular chamber or compartment 8 and an inner chamber or compartment 9. Openings 10 in the lower portion of shell 7 communicate between the inner compartment 9 and the outer compartment 8. The upper end of the inner tank or shell 7 is provided with a cover 11 in which is a draft tube 12 enclosing a propeller type circulating pump 13, which may be driven by the shaft 14 passing through a stuffing box 15 in the cover 16 of tank 1. The diphenyl oxide fills both the inner and outer compartments of the storage tank, but in the outer compartment 8 there is introduced, preferably in as compact manner as practicable, a quantity of solid material such as pig iron 17, which pig iron has a greater heat capacity per unit volume than diphenyl oxide and is also cheaper per unit volume.

18 represents a pass in the path of stack gases from a boiler, such gases being introduced at the top thereof and drawn off at the bottom as indicated by the arrows. In this pass 18, I install suitable tubular heating surface 19 here shown diagrammatically as spiral pancake-like coils in heat exchange relation with the stack gases flowing through the pass. A suitable pump 20 draws diphenyl oxide from the bottom of the tank 1 via the pipe 21 and delivers it via pipe 22 to the tubular heating system 19 from which it is led via pipe 23 back to the top of tank 1. Under normal conditions of heat storage, pump 20 will be in operation and the relatively cold diphenyl oxide from the bottom of the tank 1 will be passed through the heater 19, therein heated in countercurrent heat exchange relation with the stack gases to a temperature approximating stack gas temperature, and be delivered into the upper portion of the storage tank 1 in such heated condition. The so heated diphenyl oxide entering tank 1 will, because of its temperature, remain superimposed upon the colder diphenyl oxide below, but as the circulation proceeds the line of separation between the heated and unheated diphenyl oxide in the tank will, while remaining substantially horizontal at like level in both compartments of tank 1, gradually occupy a lower and lower level therein. That portion of the diphenyl oxide above the separating or dividing plane will have delivered a portion of its heat to the iron whereas that in the upper-most levels will be at the full temperature of introduction. Eventually the line of separation will reach the bottom of the tank and a recirculation of the charge will then occur through the heater 19, and such recirculation will then proceed until a reuse of the heat is put into effect. By adjusting the capacity for heat storage, the surface of the heater 19, and the rate of circulation to the conditions in hand, par-

ticularly where well defined peaks regularly occur in the steam load, the entire charge of diphenyl oxide and the iron submerged therein may be brought to the approximate temperature of the 5 stack gases before a reuse period starts or if a reuse period starts before such an event, there will be stored in the upper portion of the storage tank 1 diphenyl oxide of the desired high temperature and the iron filler in contact therewith will 10 be at like high temperature.

In order to reuse the so stored heat and to produce therefrom superheated steam of boiler pressure and temperature, I install within the inner shell 7 a suitable amount of water heating and steam generating surface submerged in the diphenyl oxide. Such surface is shown in the drawing in the form of pancake spiral coil assemblies 24 and 25, the upper and lower runs only of such coils being shown for the sake of 15 clearness, it being understood that substantially the entire cubic content of the shell 7 may be filled with such coils. A plan view of a preferred element of such a coil is shown in Fig. 2. By interconnecting the superimposed pancake coils, 20 a continuous coil is obtained. I then introduce water under boiler pressure to the lower-most section of the pancake coil assembly 24 via the inlet pipe 26, the water rising therein from coil to coil in spiral zigzag vertical course. By suitably relating the surface areas of coil assemblies 25 20 and 25, the water may be brought to the boiling temperature and partially vaporized in coil assembly 24. I then lead the steam and water to a steam separator 27 via the pipe 28, there- 30 in separating the steam from the unvaporized water. The latter is then led off at boiler pressure, at about boiler temperature, through the drain pipe 29 to the steam boiler not herein shown. The surviving steam is then led via 35 pipe 30 to the coil assembly 25, and the steam therein superheated in the supernatant layers of the diphenyl oxide in the shell 7 of tank 1 emerging via pipe 31 for use in a power cycle to augment that produced by the steam boiler or other- 40 wise as desired. Coincident to the introduction of water into coil assembly 24, I start the propeller pump 13 and so adjust the rate of pumping that the charge of diphenyl oxide in the tank 1 is forced down through the shell 7, around, 45 through, and past the coil assemblies 25 and 24 in sequence and out through the openings 10 in the bottom of the shell into the outer annular compartment wherein it rises. The diphenyl oxide so passed by the pump 13 over the heating 50 elements 25 and 24, countercurrent to the water passing therethrough, is cooled to approxi- 55 mately the temperature of the water entering at 26. Upon entering the outer compartment the so cooled diphenyl oxide comes into contact, 60 either immediately or shortly thereafter (de- pending upon the amount of heat which has been stored or is still available) with the pig iron therein and takes up heat therefrom, being thereby gradually heated to the initial tempera- 65 ture at which it entered the pump 13. By such circulation of the diphenyl oxide down through the shell 7 in countercurrent heat exchange relation with the water to be vaporized and then upwards through the annular compartment 8 in 70 contact with hotter and hotter iron, there will be introduced through pump 13 only highly heated diphenyl oxide until the exhaustion of substantially all of the heat stored in the diphenyl oxide and the iron from the initial high 75 temperature thereof to approximately the tem-

perature at which the said water is introduced at 26. With 700° F. initial diphenyl oxide temperature and feed water at 200° F., there will be available approximately 500° of temperature head in the diphenyl oxide and iron at the 700° level of temperature, this being accomplished by the countercurrent heat transfer relation es- 80 tablished between the diphenyl oxide and the steam generating element and the progressive absorption of heat in the iron by a rising flow of the diphenyl oxide at increasing temperature therethrough from the cooler to the hotter iron. Although I have shown the steam generating and water heating coils as divided into two por- 85 tions or assemblies 24 and 25, such division is not essential to my invention, but one coil may be used to produce steam, or more than two coils may be so used. Employing the arrangement illustrated, however, the largest possible proportion of the stored heat is made available at the high heat head and there is also furnished to the steam boiler, preheated boiler feed water at boiler temperature. It will be permissible during peak loads to suspend bleeder heating of 90 said water, thereby increasing the output capac- 95 ity of the turbine or other power mover from the normal supply of boiler steam. The steam generated from the stored heat leaving by pipe 31 may be introduced into the power mover along with the boiler steam or used otherwise as 100 desired, and during the final period of heat re- 105 covery when there is no longer a temperature head available to produce superheated steam at high pressure such steam of lower temperature may be used for any purpose available, such as 110 in a water evaporator. When little or no more steam may be generated from the stored heat, the heating of the boiler feed water may be con- 115 tinued until no further stored heat may be eco- nomically so extracted and returned to the heat 120 cycle.

Although I have illustrated the storing of heat from stack gases it is obvious that the source of heat may be high pressure steam or any other suitable high temperature source, and it is evi- 125 dent that generating unit 24-25 may be em- ployed as the heating element when storing heat, during which period high pressure steam would be passed through in the reversed direction to that when steam is generated.

Employing the construction shown in the draw- 130 ing, it will be preferable to provide baffles between adjacent pancake coils to direct the diphenyl oxide flow back and forth in a zig-zag or serpentine path, whereby both longer contact and higher velocity relations are established.

The type of heating surface and its arrange- 135 ment and other structural features are non- essential to the method of my invention, al- though preferred forms thereof have been de- scribed herein.

If storing the heat contained in boiler steam, the steam obtainable from the heat so stored will have a temperature below that of the steam used as the source of heat, but the reused heat will produce steam at a substantially uniform tempera- 140 ture level somewhat below that of the initial steam until the exhaustion of the stored heat. By combining, however, the heating of the accumu- 145 lator fluid with boiler steam and stack gases, the temperature level of the stored heat may be raised above that of the boiler steam. An arrangement for combining steam and stack gas heating may be easily made, the steam heater preceding the 150

stack gas heater relative to the flow of the accumulator fluid therethrough.

Other modes of applying the principle of my invention may be employed instead of those explained, change being made as regards the means and the steps herein disclosed, provided those stated by any of the following claims or their equivalent be employed.

I therefore particularly point out and distinctly 10 claim as my invention:—

1. In an accumulator apparatus for storing heat, the combination of a reservoir containing a heat storing high boiling point liquid, a heating device to heat said liquid, means to circulate said liquid through said heating device, an elongated tubular container vertically disposed in said reservoir, tubular means within said container for conducting a low boiling point heat receiving material therethrough, propeller means in connection 15 with said container for circulating the heat carrying high boiling point liquid therethrough over the surfaces of the tubular container for the low boiling point material, and a separator for removing unvaporized liquid from the fluid products of the low boiling point material delivered 20 from the tubular heating means therefor.

2. In an accumulator apparatus for storing heat, the combination of a reservoir containing a heat storing high boiling point liquid, a heating 25 device to heat said liquid, means to circulate said liquid through said heating device, an elongated tubular container vertically disposed in said reservoir, tubular means within said container for conducting a low boiling point heat receiving fluid therethrough, propeller means in connection with 30 said container for circulating the heat carrying high boiling point liquid therethrough over the surfaces of the tubular container for the low boiling point material and in countercurrent direction to the flow of the low boiling point material, a separator for removing unvaporized liquid from the fluid products of the low boiling point material delivered from the tubular heating means therefor, a tubular superheater in said container 35 receiving vapor from said separator and an outlet connection for delivering vapor from said tubular superheater.

3. In an accumulator apparatus for storing heat, the combination of a reservoir containing 40 diphenyl oxide, a heating device to heat said diphenyl oxide, means to circulate said diphenyl oxide through said heating device, an elongated tubular container vertically disposed in said receptacle and having an inlet connection thereto 45 at its upper end and an outlet at its bottom, tubular means within said container for conducting water therethrough, propeller means in the upper end of said container for circulating the upper strata of the hot diphenyl oxide through 50 said container over the surfaces of said tubular water vaporizing means, a separator for removing water from the steam generated, a connection 55

for delivering said separated water to a point of use, a tubular steam superheater receiving steam from said separator and located in the upper part of said container, a connection to said superheater for delivering superheated steam therefrom, and a high specific heat material piled in the annular space between the walls of said receptacle and said container for augmenting the heat storage capacity of the diphenyl oxide.

4. In a steam generating system, the method of compensating a fluctuating demand for steam which comprises absorbing and storing heat from the main boiler plant in a body of a high boiling point liquid during periods of low demand, passing water at at least the pressure of the main boiler in countercurrent heat exchange relation with said heated body of high boiling point liquid in an auxiliary boiler during periods of higher steam demand, whereby to heat the water to the vaporizing temperature thereof at the existing pressure, separating the so generated steam from the water, forwarding the hot water as feed water to the main boiler and forwarding the steam to a point of use.

5. In a steam generating system, the method of compensating a fluctuating demand for steam which comprises absorbing and storing heat from the main boiler plant in a body of a high boiling point liquid during periods of low demand, passing water at at least the pressure of the main boiler in countercurrent heat exchange relation with said heated body of high boiling point liquid in an auxiliary boiler during periods of higher steam demand, whereby to heat the water to the vaporizing temperature thereof at the existing pressure, separating the so generated steam from the water, forwarding the hot water as feed water to the main boiler, superheating the so separated steam by passing the same in heat exchange relation with the hottest portion of the body of high boiling point liquid and forwarding the superheated steam to a point of use.

6. In a steam generating system, the method of compensating a fluctuating demand for steam which comprises circulating a body of a high boiling point heat-storing liquid in heat exchange relation with the hot stack gases from the main boiler plant to absorb heat therefrom, passing water at at least the pressure of the main boiler in countercurrent heat exchange relation with the said heated body of high boiling point liquid in an auxiliary boiler, whereby to heat the water to the vaporizing temperature thereof at the existing pressure, separating the so generated steam from the water, forwarding the hot water as feed water to the main boiler, superheating the so separated steam by passing the same in heat exchange relation with the hottest portion of the body of high boiling point liquid and forwarding the superheated steam to a point of use.

JOHN J. GREBE.
